UNITED STATES PATENT OFFICE.

JAMES P. ELMER, OF ST. PAUL, MINNESOTA, ASSIGNOR TO MOORE PATENT CAR COMPANY, A CORPORATION OF SOUTH DAKOTA.

HEATER-CAR.

1,156,988.

Specification of Letters Patent.

Patented Oct. 19, 1915.

Application filed April 12, 1910. Serial No. 555,122.

To all whom it may concern:

Be it known that I, JAMES P. ELMER, a citizen of the United States, residing at St. Paul, in the county of Ramsey and State of Minnesota, have invented a new and useful Improvement in Heater-Cars, of which the following is a specification:

My invention relates to improvements in heating apparatus for cars, and has among its objects the equalization of heat in all parts of the lading chamber and the removal of foul and cold air from the bottom of the car. The apparatus to accomplish this, is easily regulated to meet different degrees of cold and is operated from the outside of the car so that the car doors need not be open admitting freezing air to the lading chamber. The heater and connected air ducts are simple in construction and easily built into insulated or refrigerator cars either new or old. I have chosen to show my device in connection with a car having double walls and floor with air passages between which facilitate the equalization of temperature within the car and surround the lading chamber with an envelop of air moving through these passageways.

My device overcomes the usual objections to stoves and oil lamps and the accompanying soot and foul gases by the use of a blue flame oil burner; and provides a constant supply of fresh pure air for the provision chamber. It does not take up space in the car and is easily removed or renewed.

In the drawings that illustrate my device constituting part of the specification, Figure 1 represents the sectional top view of an insulated car showing insulating and air spaces in the car walls and the location of the heater; Fig. 2 is a section on the line A—A of Fig. 1 showing air spaces in the end and bottom of the car and the position of the heater and the air ducts; Fig. 3 is an enlarged view of a portion of Fig. 2 showing heater and air passages; Fig. 4 is a section on the line B—B of Fig. 3; Fig. 5 is an elevation of the box containing the heater showing the location of the doors; and Fig. 6 is a section on line C—C of Fig. 5.

Similar numerals are used to indicate identical parts in the different views.

In my device as illustrated, 2 is an air

space between side walls 3 and 4, extending down the side and ends of the car between nailing strips 5 and opening into the air spaces 6 between floors 7 and 8. Insulating material 9 lies between the floor 8 and the exterior of the car. Beneath one side of the car is hung box 10 containing blue flame burners 11, oil tank 12, feed tank 13 and feed pipe 14. Box 10 has double walls 15 and 16 with insulating material between and doors 34 and 35 and is suspended from the car body by means of bolts or other suitable means. Through the bottom of box 10 pass inlet pipes 17 supplying fresh air to the interior of the box. Above the opening of inlet pipe 17 is deflecting plate 18. Above the burners 11 extend connection flues 19 to a common drum 20 to which they are connected by movable sleeves 21 for convenience in removing the flies. These sleeves can assume dotted position 22. Extending upward from the drum 20 are hot air ducts 23. These ducts pass through floors 8 and 7 and extend upward through air space 2 and open into the lading chamber near its top through openings 24. Surrounding hot air ducts 23 is the ventilating passageway or duct 25 formed by two pieces of sheet metal 26 and 27. Of these pieces 26 rests upon floor 8 while 27 rests upon floor 7 and both parts are secured to the wall 3 which is interrupted at this point to give greater space for the air duct. Pieces 26 and 27 forming 25 the ventilating passageway extend to near the top of the lading chamber where they are reduced to meet two pipes 28 which pass through the roof of the car and open to the outer air through ventilators 29. Plate 27 resting on floor 7 allows space 6 between floors 7 and 8 to connect with the ventilating passageway 25 through openings 31. Plate 27 also has holes 30 close above floor 7 allowing the air in the bottom of the lading chamber to flow into the ventilating passageway 25. Burners 11 have an automatic oil feed so that they cannot be flooded and can be burned singly or together. Wall spaces 2 communicate with the lading chamber through slots 32 immediately above the floor 7 which extend across alternate spaces between the vertical nailing strips 5.

In operation the car is loaded and the

doors closed, one or both of the blue flame burners are lighted according to the temperature to which the car is subjected. The heat of the burners causes the air within the hot air ducts 19 to rise into the drum 20 and through the hot air ducts 23 into the top of the lading chamber. As this takes place fresh air is supplied to the burner through the inlet pipes 17. The passage of the heated air through the ducts 23 tends to warm the walls of these ducts and the surrounding air within the ventilating passageway 25. As this air rises and escapes through the ventilators 29 the cold air in the bottom 15 of the lading chamber enters through apertures 30 and 31 and completes the circulation through the lading chamber. By means of this circulation, the warm fresh air is passed into the chamber at the top while 20 the cold air and any foul gases that may arise from the load are drawn off through the ventilating passage. At the same time the air within the wall spaces 2 becoming cool by the radiation of heat through the 25 outer walls of the car will tend to settle downward into the space under the floor 7 and enter the ventilating passages 25 through opening 31 where it is heated by the duct 23 and rises out through the roof 30 ventilators as mentioned above. As the cold air in wall space 2 settles downward it is replaced by warm air from the top of the lading chamber drawn into the air space 2 through opening 33. Thus warm air is 35 constantly circulating downward in the wall spaces and under the floor of the car. This completes the circulation through the heater, the lading chamber, the wall and floor spaces to the ventilating passage and 40 the open air, and it is clear that the warm air supplied by the heater to the lading chamber can flow to the ventilators by one of three routes, viz. downward through the load, and then through openings 30; 45 through wall space 2 and back into the lading chamber through openings 32; or through the wall space 2 into the floor space 6 and thence to the ventilators through opening 31. The flow of air through any of 50 these routes is equally efficient in repelling cold from without and conserving the heat energy imparted to the air by the burners, and the air will follow the route offering the freest flow, and will follow all to some extent.

In the construction of heater box 10, the interior walls 16, the partitions 36 and 37 and the sheathing 38 are constructed of fire-proof material or rendered fireproof in any 60 suitable manner. A drain pipe 39 is also provided in the compartment containing the oil supply tank 12. In this way each burner 11 is completely isolated from the oil supply tank and from the adjoining burner and any 65 spilling or leakage of oil at the tank or at

connections to the feed pipe 14 will drain away, without spreading to the entire heater with the accompanying danger from fire. The isolation of the oil supply tank and the fireproofing of the adjacent parts will 70 greatly decrease the danger from fire in case the heater car is wrecked, while in service.

In accordance with the patent statutes I have described the principles of operation of my invention together with the apparatus 75 which I now consider to represent the best embodiment thereof but I desire to have it understood that the construction shown is only illustrative and that the invention can be carried out by other means and applied 80 to uses other than those above set forth within the scope of the following claims.

Having described my invention, what I claim as new and desire to protect by Letters Patent is:—

1. A car body having double walls and a double floor forming communicating air passages which also communicate with the upper and lower portions of the lading chamber, a closed heater chamber below the 90 car body having an air inlet to admit fresh air, a ventilating flue extending from the bottom to the top of said car body having a communication near its lower end with said air passages in the floor of said body, a communication near its lower end with the lower portion of the lading space within said body and an exit near its upper end to the outer atmosphere, a plurality of heaters in said heater chamber, and a hot air 95 duct from each of said heaters passing upwardly through said ventilating flue and into the upper portion of the lading chamber, whereby one or more of said heaters may be operated and warm air circulated 100 into the upper portion of the lading chamber and cold viviated air is conducted from the lower portion of the lading chamber through the passages in the floor of the car body and directly into the ventilating flue 110 and thence to the outer atmosphere, said hot air ducts being adapted by contact of the surfaces of their walls with the air in said ventilating flue to heat and drive the cold viviated air received from the car body to 115 the outer atmosphere.

2. A car body having a passage in its floor communicating with the lower portion of its lading chamber, a ventilating flue comprising plates forming a conduit recessed into the wall of the car, part of said plates forming the innermost and side walls of said conduit and the remaining forming a cover for the conduit lying substantially flush with the inner surface of the wall of 120 the car body, the lower end of said conduit being in communication with said passage in the floor of the car body, and the cover of said conduit being formed with openings 125 near the floor of the car body for conducting 130

cold and vitiated air from the lower portion of the lading chamber into said conduit, a heater near the lower end of the conduit and a hot air flue in connection with said heater 5 passing upwardly through said conduit and opening into the upper portion of the lading chamber, for the purposes specified.

In testimony thereof, I have signed my name to this specification, in the presence of two subscribing witnesses.

JAMES P. ELMER.
